UNITED STATES PATENT OFFICE.

FRANK E. BECKMAN, OF HAVERHILL, MASSACHUSETTS, ASSIGNOR TO UNITED SHOE MACHINERY COMPANY, OF PATERSON, NEW JERSEY, A CORPORATION OF NEW JERSEY.

SHOE-SEWING MACHINE.

1,101,238.

Specification of Letters Patent. Patented June 23, 1914.

Application filed January 20, 1912. Serial No. 672,470.

To all whom it may concern:

Be it known that I, FRANK E. BECKMAN, a citizen of the United States, residing at Haverhill, in the county of Essex and State of Massachusetts, have invented certain new and useful Improvements in Shoe-Sewing Machines; and I do hereby declare the following to be a full, clear, and exact description of the invention, such as will enable others skilled in the art to which it appertains to make and use the same.

The present invention relates to shoe sewing machines and particularly to those types of machines which are employed to sew the welt to a lasted shoe.

In welt sewing machines of the type illustrated, as now commonly built, the work is fed by a feed point and a channel guide which are moved in the direction of the feed of the work by a longitudinally moving feed slide, and are held in engagement with the work during the work feeding movement of the slide. After the needle has penetrated the work, the feed point and the channel guide are released from the work and moved back along the line of feed in preparation for the next feeding movement. The welt is positioned against the shoe by means of a welt guide through which the welt is drawn. During the retractive stroke of the needle the welt guide is locked against the work, acting to hold the welt against the shoe so that it cannot be drawn away from the shoe by the retraction of the needle. After the needle has reached the limit of its retractive stroke and is stationary, the welt guide is withdrawn backwardly at right angles to the surface of the work, which is fed along by the feed point and channel guide simultaneously with the backward movement of the welt guide. The combined movements of the welt guide and the work act to "measure" through the welt guide a sufficient length of welt for the next stitch. Such a movement of the welt guide in measuring the welt involves certain disadvantages. The movement of the welt guide away from the work at right angles tends to pull the welt away from the work and to loosen the preceding stitch. Such a movement of the welt guide is also at substantially a right angle to the plane in which the welt strip lies in its approach to the work, so that the welt strip is bent sharply as it emerges from the mouth of the welt guide aperture

and is not drawn freely from the welt guide aperture.

One object of the present invention is to provide improved means whereby the welt may be freely drawn or "measured" through the welt guide.

With this object in view, the present invention contemplates improved means whereby the welt guide shall have its welt measuring movement take place in the plane in which the welt normally lies in its approach to the work. Such movement may preferably, but not necessarily, occur at the time when the work is positively locked in position by the needle.

The present invention also contemplates imparting to the welt guide a movement of approach to the surface of the work to press the welt against it, and simultaneously a movement in the direction of feed of the work. The welt guide, in moving in the direction of feed of the work, serves to carry the welt along with the shoe and so assists the feed point and channel guide in feeding the work. The welt guide, by virtue of its combined movements of approach to the work in the direction of feed, acts to press the welt into position, and also to gather or crimp the welt against the shoe, since in sewing, especially around the curved parts of the shoe, it is desirable that the welt should not be stretched along the line of stitching, but should be loosely laid or even pushed forward to be gathered or crimped slightly along the line of stitching which unites it with the insole, for the reason that when the welt is subsequently laid flat the length of its outer edge is greater than that of the inner edge where it is sewn to the insole. Since the welt guide measures the welt while the needle is in the work, the welt guide will have assumed a position away from the surface of the shoe at the time when the needle is being retracted through the work, and hence it is desirable that some means be employed to hold the welt against the shoe to prevent its being lifted by the backward loop-drawing movement of the needle.

The present invention contemplates the employment of means, such as a work-engaging finger, which shall be held against the welt in the neighborhood of the stitch being formed during the retractive movement of the needle to prevent the welt from

being lifted from the shoe. This work engaging finger also bears against the work while the welt guide is being swung backwardly away from the work, and will resist any tendency that the backward movement of the welt guide might have to lift the welt guide from the shoe.

Other features of the present invention relate to certain constructions, arrangements 10 and combinations of parts hereinafter described, the advantages of which will be apparent to those skilled in the art from the following description.

In the drawings the preferred embodiment 15 of the invention is illustrated in connection with the well-known Goodyear welt and turn machine which is illustrated and described in the patent to French and Meyer No. 412,704, October 8th, 1889, this sewing 20 machine of French and Meyer being provided with the thread tension releasing device of La Chapelle No. 488,505, December 20, 1892, as is usual in the present commercial type of machine. It is to be understood, 25 however, that the invention is equally applicable to other types of sewing machines, and that it can be otherwise embodied without departing from the spirit of our invention.

30 Referring to the drawings, Figure 1 is a front elevation of the head of the machine embodying the preferred form of our invention; Fig. 2 is a side elevation taken partly in section looking from the right-hand side 35 of the machine; Fig. 3 is a side elevation taken partly in section looking from the left-hand side of the machine; Figs. 4 and 5 are sectional views taken on the line X—X of Fig. 2; Fig. 4 indicating the position of 40 the parts as the work is about to be fed forwardly, and Fig. 5 indicating their position after the work feeding motion has taken place; Figs. 6, 7 and 8 are fragmentary sections taken on the line X—X of Fig. 2 and 45 illustrating different steps of the needle threading operation; and Fig. 9 is a view showing a vertical section of the welt guide.

Referring to the drawings, 1 indicates generally the frame of the machine in which 50 is journaled the driving shaft 2 which bears the cam wheels for actuating the various stitch forming means.

3 indicates the feed point or awl, and 4 the channel guide, both of which are carried 55 by the longitudinally reciprocating feed slide 5, and given a motion to and from the work by the cam-operated levers 6 and 7 respectively.

8 indicates the curved hook needle operated 60 by suitable levers and cams, and 9 indicates a take-up which coöperates with the other usual thread rolls in controlling the supply of thread to the needle and the work, which is shown as the insole 10 and upper 65 11 of a lasted shoe to which is being sewn

a welt 12. At the left of the machine is shown the link 13 which is broken away at its lower portion, and which is employed to operate a thread tension release upon the reverse rotation of the operating shaft, the 70 notch 14 in the operating shaft engaging the ratchet tooth or catch 15 upon the link and depressing it when the direction of rotation of the operating shaft 2 is reversed. The forward direction of rotation of the 75 shaft 2 is indicated by the arrow in Fig. 3.

The above parts are constructed and arranged to operate in a well-known manner, substantially as set forth in the French and Meyer and the La Chapelle patents, and further description thereof is considered unnecessary.

The welt guide 16 is pivotally mounted upon the forward end of a sliding bar 17 which is normally held in its forward position by a helical spring 18 to hold the welt guide in engagement with the work. The forward movement of the slide bar 17 under the action of its spring is limited by a shoulder 19 formed upon the slide bar which is adapted to strike against the adjustable screw 20 mounted in a fixed part of the machine frame. By adjusting the screw 20 the forward limit of the movement of the welt guide may be varied at will. The slide bar 95 17 is normally locked in its forward position by the engagement of a locking pawl 21 with the ratchet teeth 22 formed upon the slide bar. The locking pawl 21 is carried upon one arm of a cam-operated lever 23 which is actuated by a cam roll 24 running in a cam path formed in the side of a cam wheel mounted upon the driving shaft 2. This cam path is so timed with relation to other parts of the machine that the cam roll 100 24 will actuate the lever 23 to raise the pawl 21 against the tension of the spring 25, which normally holds it in engagement with ratchet teeth 22, and release said locking pawl from the bar 17 while the work is fed 105 forwardly and the needle penetrates the work. This locking device and its release are substantially the same as that described in the above-mentioned French and Meyer patent. The welt guide is arranged to be withdrawn from the work upon the reversal 110 of the machine by the retraction of the sliding bar 17 sufficiently to permit the shoe to be disengaged from the channel guide and easily removed. A pin 26 projecting from the side of the sliding bar is adapted to be engaged by a finger 27 which is rigidly carried upon a shaft 28 journaled in the machine frame. The outer end of the shaft 28 is provided with a slotted arm 29 which is engaged by a pin on the link 13 when said link is depressed by the engagement of the notch 14 with the teeth 15 when the operating shaft is turned in a reverse direction. The downward motion of the link 13 is 115 120 125 130

communicated to the slotted arm 29, turning the shaft 28 and moving the finger 27 against the pin 26, thus retracting the sliding bar 17 together with the welt guide 16.

5 The notch 14 is so positioned upon the cam shaft with respect to the cam which operates the release lever 23 that the slide bar will be retracted on a reverse rotation of the shaft at the time when the locking pawl 21 is disengaged.

10 The welt guide 16 may be slightly withdrawn from the work by the retraction of the sliding bar 17 during the work feeding part of each cycle of the stitch forming 70 operation. This retraction may be imparted to the sliding bar 17 by the engagement of a swinging pawl 30 with the ratchet teeth 31 carried upon the sliding bar. The pawl 30 is normally held in engagement with the 75 ratchet teeth 31 by a spring 32, and is given a swinging motion back and forth along the line of the slide bar by a lever 33, upon whose end said pawl is pivotally mounted. The lever 33 receives an oscillatory motion 80 from the cam roll 34 carried by the upper end thereof and running in a cam path formed in the side of a cam wheel carried by the shaft 2. When the pawl 30 is swung backwardly, it engages the teeth 31 and 85 moves back the slide bar 17. When the pawl is swung forwardly it rides over a shield 35 which lifts its point from engagement with the ratchet teeth 31, and allows the slide bar 17 to freely move forwardly under the tension of the spring. To vary the point of 90 engagement and disengagement of the pawl 30 from the ratchet teeth 31 and thus determine the amount of retractive movement that it imparts to the sliding bar 17, the shield 35 is 95 adjustable upon the machine frame and held thereto by a clamping screw 36 engaging through a slot 37 in the shield piece. The position of the ratchet 31 beneath the pawl 30, when the welt guide is pressed 100 against the work, is determined by thickness of the work engaged. The pawl 30 has a fixed amount of backward swing and upon its engagement with the ratchet teeth moves the sliding bar back a predetermined distance regardless of thickness of the work.

105 The welt guide 16 is mounted upon the forwardly extending arm 38 of a lever 39 which is pivotally mounted to oscillate in a horizontal plane about a fulcrum pin 40 on an offset bracket 41 which is rigidly secured to the forward end of the sliding bar 17. The sliding bar 17 has a spline 42 engaging in a suitable groove in the bracket 41 and an adjustment between the bracket and sliding bar 110 is secured by a clamping screw 43 engaging through a slot 44 in the sliding bar. The forwardly extending arm 38 is offset to the right to some extent so that when the lever 39 is oscillated about its pivot the welt guide 115 16 carried upon the end of the offset arm

will approach the work when it is swung to the left during the feeding of the work and will be retracted from the surface of the work when it is swung back along the line of feed to the right. As is common in this type of machines, the roll of welting is laid on a bench or table at the right of the machine, and is drawn over a hook 16^a, passing somewhat forwardly to the welt guide and the shoe. The swinging movement of the 75 welt guide to the right and to the rear is thus along the lead of the welt in substantially the same plane in which the welt normally lies in its approach to the work. The lever 39 has a rearwardly extending arm 80 formed with a recess 45 in which is journaled a cylindrical block 46, which is also free to slide longitudinally in the recess. The cylindrical block 46 is transversely bored to form a journaled and a sliding bearing for 85 the end of a pin 47 which extends forward from the lower end of a lever 48. The lever 48 is adapted to be oscillated in a vertical plane about a fulcrum 49 which secures it to the machine frame. The swinging motion of 90 the pin 47 is communicated through the sliding block 46 to the lever 39. The sliding engagement of the block 46 in its recess and the journaled and sliding engagement of the pin 47 in the block 46 allows the motion of 95 the pin 47 which is swung from a pivot 49 upon a fixed part of the machine frame, to be communicated to the welt guide lever which is pivoted upon the sliding bar 17 which is movable relatively to the machine frame on a line inclined to the horizontal. The lever 48 receives its oscillatory motion 100 through a link 50 which is pivoted at 51 to the upper end of said lever. The other end of the link 50 is pivoted at 52 to the forwardly offset arm 53 of a lever 54 which is pivotally mounted to oscillate about a pin 55 carried by the the machine frame. The lever 54 is formed of two approximately 105 parallel arms 56 and 57 which afford two somewhat separated bearings upon either end of the pin 55 whose middle portion is held in a bored lug 58 upon the machine frame. The somewhat separated bearings of the two arms 56 and 57 upon the pin 55 110 prevent the lever 54 from twisting about a vertical axis and binding against the pivot pin, which it would have a tendency to do in case a single bearing were employed, since the point at which it applies its force 115 to the link 50 is offset forwardly from the lever. The lever 54 receives its oscillatory motion from a reciprocating link 59. The end of the link 59 is received by the bifurcated end of a sliding bar 60 which actuates 120 the swinging back rest to be hereafter described. A pin 61 pivotally connects the link 59 to the bar 60. The ends of the pin 61 extend laterally from the sliding bar 60 and are journaled in blocks 62 which are slid- 125 130

ably mounted in recesses 63 formed in the bifurcated lower end of the lever 54.

The sliding engagement of the blocks 62 in the recesses 63 allows the reciprocatory motion of the end of the link 59 to be transformed into an oscillatory motion of the lever 54. The link 59 receives its reciprocatory motion from a lever 64 to the lower end of which it is pivotally connected by a pin 65 adjustably held in a curved slot 66. The lever 64 is given an oscillatory motion by means of a cam roller 67 which runs in a cam path 68 formed in the periphery of a cam wheel carried by the driving shaft 2. The lever 64 has an oscillatory motion of a fixed amount, but the amount of movement which it communicates to the link 59 may be varied by adjusting the position of the pivot pin 65 in the curved slot 66 at the lower end of the lever 64. The motion of the lever 64 is thus communicated through the connecting chain of links and levers to the welt guide 16 which is positively oscillated about its pivot to give it a motion in the direction of feed and toward the surface of the work, and a motion backwardly along the line of feed and away from the surface of the work. Since the welt in its approach to the shoe lies in a plane which is slightly inclined to the surface of the shoe, the movement of the welt guide is in substantially the same plane in which the welt normally lies, so that when the welt guide is moved backwardly the welt will be freely drawn or measured through the welt guide and when the welt guide is moved forwardly the welt will be moved against the surface of the work and slightly gathered thereon. The degree to which the welt is gathered against the shoe may be varied by varying the amount of movement imparted to the welt guide. If the welt guide be moved backwardly to measure off a length of welt equal to the distance that the shoe is fed, the welt will be merely laid against the shoe and not gathered. However, if the welt guide be moved backwardly to measure off a length of welt greater than the distance that the shoe is fed, the forward movement of the welt guide will cause it to move in the direction of feed slightly faster than the shoe, and will crimp or gather the welt against the shoe. The amount of gathering, if any, which it is desired to give to the welt may be determined for any particular machine by suitably proportioning the welt guide mechanism.

In order that the welt shall be firmly held against the shoe during the retractive movement of the needle, a forwardly projecting work-engaging finger 69 is formed on the bracket 41 to which the welt guide is pivoted, which prevents the welt from being drawn away from the shoe by the backward pull of the needle through it or by the meas-

uring movement of the welt guide. Since the offsetting of the welt guide to one side of its pivot point causes its oscillatory movement to move it forward against the surface of the work and to retract it from the surface of the work, it is possible to entirely dispense with the retracting pawl 30, together with its operating means, for withdrawing the sliding bar, and thus considerably simplify the construction of the machine. Or, if it is so desired, the pivoted welt guide may be used in conjunction with the pawl retracted slide bar, as illustrated in the present construction. It is to be understood, however, that the use of the pivoted welt guide mounted upon a forwardly spring-pressed slide bar which is not provided with retracting means, or the use of the welt guide pivoted directly to the frame of the machine, is contemplated within the spirit of the invention.

The back rest 70 is formed on the front of a bell crank lever 71 which is pivotally mounted at 72 upon the offset forward end of a sliding bar 73. The work engaging face of the back rest is curved on the arc of a circle with the pivot point 72 as a center so that as the back rest oscillates about its pivot, the surface of the back rest is swung along the direction of feed without movement of approach to or recession from the work. The sliding bar 73 is pressed forwardly by a spiral spring 74 and is locked in its forward position during a part of the stitch forming operation by a pawl 75 and ratchet wheel 76. The construction and operation of said spring and said bar locking mechanism is substantially the same as that disclosed in the above-mentioned French and Meyer patent. The bell crank lever 71 is given an oscillatory motion about its pivot 72 by a link 77 pivotally connected thereto at 78. The other end of the link 77 is pivoted at 79 to one arm of a bell crank lever 80 and receives a reciprocatory motion from the oscillation of said bell crank lever. The bell crank lever 80 is fulcrumed at 81 to the sliding bar 73 and carries at the end of its other arm a sliding block 82 which is held in a box 83 to freely slide in a direction parallel to the direction in which the bar 73 is slidable. The box 83 is rigidly mounted upon one end of the sliding bar 60 which reciprocates in the machine frame at right angles to the direction in which bar 73 is slidable.

The motion imparted to the block 82 by the reciprocation of its containing box 83 oscillates the lever 80. The sliding engagement of the block 82 in the box 83 allows the reciprocatory motion of the bar 60 to be transformed into an oscillatory motion of the lever 80, and also provides for the transfer of motion between these parts regardless of the position of the sliding bar 130

73 in the machine, since it is evident that motion will be imparted to the block 82 in whatever place it may chance to be, in the box due to varying position of the sliding bar 73 to which the lever 80 is fulcrumed. The sliding bar 60 pivotally receives in its bifurcated end the link 59 which imparts a reciprocatory motion thereto, and which also, as previously described, 10 actuates the welt guide mechanism. The motion of this common link 59 and its actuating lever 64 is communicated through the above described system of links and levers to the back rest 70, which is thus given a 15 motion to and fro along the line of feed of the work. The timing of the cam path 68 is such that both the welt guide and the back rest will swing along with the work and assist the feed point and channel guide 20 when they feed the work in preparation for a stitch, and that motion of the back rest and welt guide backwardly along the line of feed of the work to position the back rest and welt guide in preparation for the next 25 feeding movement and to draw the welting strip through the welt guide, will take place while the work is positively locked in position by the penetration of the needle therethrough.

30 The welt guide is illustrated in detail in Fig. 12. The upper wall 84 of the welt receiving aperture is formed directly on the welt guide lever 39 and has a rib 85 to engage in the groove in the welting strip 12. 35 The front and lower walls of the welt receiving aperture are formed of a guide plate 86 whose two ends have slots 87 for the reception of clamping screws 88 by which it is adjustably held to the arm 39. The 40 clamping screws and slots allow the guide plate 86 to be adjusted to vary the depth of the welt receiving aperture to accommodate for welts of different thickness. The back wall of the welt guiding aperture is 45 formed by a gage piece 89. The thread finger 90 is formed of two thread-engaging prongs 91 and 92 carried upon the end of an arm 93 which projects radially from a shaft 94. The shaft 94 is slidably received 50 in a bushing 95 mounted in the bracket 96 of the machine frame. The interior of the bushing 95 is provided with a spiral slot 99 in which is engaged a pin 100 projecting from the shaft 94. When the shaft 94 is 55 reciprocated, the pin 100 and the spiral slot 99 give the shaft 94 a motion of rotation as well as reciprocation, and move the thread finger 90 in a spiral path. The forward motion of the thread finger is in the direction of the projection of the prongs 91 and 92 so that the thread is engaged between the prongs. The end of the shaft 94 opposite to the thread finger arm is formed with an enlarged head 101 which is received in a 65 recess 102 formed in the lower end of a

bell crank lever 103 pivoted at 104 to the bracket 96. The oscillatory motion of the bell crank lever 103 gives to the shaft 94 a reciprocatory motion, the ball and socket connections allowing the head 101 to both 70 slide and turn in the recess 102. The other arm of the bell crank lever 103 is slotted at 105 and has adjustably clamped in said slot a pin 106 to which is pivoted one end of a link 107. The other end of the link 75 107 is pivotally held at 108 on a sliding block 109 whose reciprocation oscillates the bell crank lever 103. The adjustment of the pin 106 in the slot 105 allows the amount of oscillation given to the bell crank lever 80 by the reciprocation of the block 109 to be varied. The block 109 is slidably held in a suitable box 110 which is rigidly mounted upon the machine frame. The sliding block 109 bears upon its upper end a roller 111 85 which is received in a cam path 112 cut in the side of a cam roller 113 mounted upon the driving shaft 2 of the machine. The timing of the cam path 112 is such that the thread finger 90 will engage the thread and carry it behind the point of the needle 8 after the needle has penetrated the work.

90 The looper eye 114 which co-operates with the thread finger in threading the barb of the needle is carried on a block 115 slidably mounted in the bifurcated lower end 116 of the looper lever 117. The looper lever 117 is fulcrumed near its center on the pivot pin 118 held in a bifurcated head 119. The head 119 is pivotally mounted upon the machine frame by a pin 120 engaging in a suitable socket formed in the machine frame. This arrangement gives the looper lever 117 freedom to swing in all directions about the point 118. The lower arm of the lever 117 is longitudinally recessed to receive a sliding bar 121 to whose lower end is rigidly secured the block 115. The upper end of the bar 121 has secured thereto a head 122 which is laterally recessed to slidably receive a 100 block which is pivotally mounted at 123 on one arm of a bell crank lever 126 which is fulcrumed at 127 to an ear formed upon the lever arm 117. The other arm of the bell crank lever 126 is formed with segmental gear teeth 128 which mesh with the segmental gear teeth 129 formed upon the head 119. When the lever 117 is turned about the pivot pin 118 to move the looper eye 114 outwardly, the fulcrum 127 of the bell crank 105 lever 126 will also move outwardly from beneath the head 119. The gear teeth 128 are, however, held by their meshing engagement with the gear teeth 129 so that the bell crank lever 126 is turned and the bar 121 moved downwardly, which imparts to the looper eye a motion downwardly as well as forwardly. The looper lever 117 receives its motion from a cam wheel 130 mounted on the driving shaft of the ma- 110

chine. A roller 131 borne upon the upper end of the lever 117 is received in a cam groove 132 cut in the periphery of the cam wheel 130 and oscillates the lever 117 about the axis of the pivot pin 120. The upper end of the lever 117 also bears two rollers 133 which bear against peripheral cam surfaces 134 formed on the periphery of the cam wheel 130. The cam rollers 133 give the lever 117 a movement of oscillation about the pin 118. The cam rollers 133 are held in engagement with peripheral cam surfaces 134 by a spring 135 which is received in a suitable recess formed in a bracket arm 136 of the machine frame. One end of the spring 135 is held against an adjusting screw 137 while the other end presses downwardly against a sliding block 138 in which is formed a socket 139 receiving one end of a ball-ended link 140 whose other end is received in a similar socket 141 formed on the top of the lever arm 117. The form and timing of the cam paths which actuate the looper lever is such that after the thread finger has engaged and carried a bight of thread behind the point of the needle, the looper eye will move forwardly and downwardly in a curved path around the side of and to the front of the needle, drawing the thread into the needle barb. The end of the needle during the looping operation is directed forward and upward at an angle of about 45° to the horizontal, while the supporting point of the lever 117 is substantially vertically above the looper eye and therefore at one side of the axis of the end portion of the needle shank. The combined oscillatory movement of the lever 117 and the reciprocatory movement of the bar 121 cause the looper eye 114 to travel about the barbed end of the needle in a curved path lying in a plane approximately normal to the end of the needle, so that the bight of thread between the thread finger and looper is laid in the needle barb more nearly at right angles to the needle shank and the needle does not need to be projected as far forwardly as would be necessary if the looper eye did not move relatively to the looper lever, in which case the looper eye would move forwardly in a curved path lying in an approximately horizontal plane.

The operation of the machine, particularly that of the improvements in which the present invention is embodied, is as follows: Starting in the position shown in Fig. 4, in which the feed point and channel guide have just engaged the work, the feed point and channel guide are moved along to feed the work. Simultaneously with the movement of the feed point, the back rest and welt guide are swung along in the direction of feed of the work, the welt guide moving into engagement with the work and pressing

and gathering the welting strip against the shoe. The parts have assumed the position illustrated in Fig. 5. The needle now descends and pierces the work, as shown in Fig. 6. After the needle has pierced the work, the feed point, channel guide, back rest and welt guide are moved backwardly along the line of feed in preparation for the next feeding stroke, as shown in Fig. 8, the welt guide measuring off the welt for the next stitch. After the needle has pierced the work and is held in its forward position, the thread finger moves to the right in a spiral path, catching the thread between its prongs and taking a bight of thread across the place of oscillation of the needle above the horizontal portion of the needle shank and behind the barbed end of the needle, the parts assuming the position shown in Fig. 7. The looper now moves in a curved path forwardly in front of the needle and downwardly, laying the thread across the needle and pulling it into the needle barb, the parts assuming the position shown in Fig. 8. After the needle is threaded, it is retracted and the feed point and channel guide again engage the work, as shown in Fig. 4, which completes one cycle of the stitch forming and work feeding operations. Since the thread finger moves behind the needle and the motion of the looper is forwardly and along the path curved only sufficiently to lay the thread against the barb of the needle, the needle on its retraction will draw the thread through the work in an untwisted loop, as illustrated in Fig. 4.

While the preferred embodiment of the invention has been specifically illustrated and described, it is to be understood, however, that the present invention is not limited to the exact details of the illustrated embodiment but may be otherwise embodied within the spirit of the invention and the scope of the following claims:

1. An inseam shoe sewing machine having, in combination, stitch forming devices including a curved hook needle, and a welt guide having independent movements of reciprocation at substantially right angles to the direction of feed of the work and of oscillation toward and from the shoe substantially along the lead of the welt.

2. An inseam shoe sewing machine having, in combination, stitch forming devices including a curved hook needle, a sliding bar arranged to reciprocate at an angle to the direction of feed of the work and a welt guide pivotally mounted upon the sliding bar to oscillate toward and from the shoe substantially along the lead of the welt.

3. An inseam shoe sewing machine having, in combination, stitch forming devices including a curved hook needle, a sliding bar arranged to reciprocate at substantially right angles to the feed of the work, a welt

- guide pivotally mounted on said bar to oscillate toward and from the shoe substantially along the lead of the welt and means including a sliding connection for oscillating 5 the welt guide independently of the movement of the sliding bar.
4. An inseam shoe sewing machine having, in combination, stitch forming devices including a curved hook needle, a welt guide 10 pivotally mounted to swing on an axis substantially at right angles to the surface of the welt and offset to one side of its pivot point whereby it is given motion to approach and recede from the work as it is oscillated 15 about its pivot, and means for oscillating said welt guide about its pivot.
5. An inseam shoe sewing machine having, in combination, stitch forming devices including a curved hook needle, a sliding 20 bar, a welt guide pivotally mounted upon said bar, to swing on an axis substantially at right angles to the surface of the welt, said welt guide being offset to one side of its pivot point, means for moving the said bar 25 forwardly to move the welt guide toward the surface of the work, and means for oscillating said welt guide about its pivot to give it an additional movement toward the surface of the work.
- 30 6. An inseam shoe sewing machine having, in combination, stitch forming devices including a curved hook needle, a welt guide pivotally mounted to swing on an axis sub-

stantially at right angles to the surface of the welt, and means to positively oscillate 35 the welt guide about its pivot to cause it to approach the work in an arc of a circle while the work is being fed and to recede backwardly along the same arc after the feeding movement of the work has taken place. 40

7. An inseam shoe sewing machine having, in combination, stitch forming devices including a curved hook needle, a welt guide and means for moving the welt guide toward and from the work substantially along the 45 lead of the welt.

8. An inseam shoe sewing machine having, in combination, stitch forming devices including a curved hook needle, mechanism for feeding the work including a member 50 arranged to engage the channel of a lasted insole, and a welt guide arranged to be moved toward the work substantially along the lead of the welt.

9. An inseam shoe sewing machine, having, in combination, stitch forming devices including a curved hook needle, a slide mounted to move toward and from the shoe, a work holding finger mounted on the slide and a welt guide pivotally mounted on the 55 slide to oscillate substantially along the lead of the welt.
